United States Patent Office.

TRUMAN C. PHINNEY AND CHARLES E. BANCROFT, OF MONTPELIER,
VERMONT.

Letters Patent No. 96,034, dated October 19, 1869.

IMPROVEMENT IN SPOUTED CANS.

The Schedule referred to in these Letters Patent and making part of the same.

To all whom it may concern:

Be it known that we, TRUMAN C. PHINNEY and CHARLES E. BANCROFT, of Montpelier, in the county of Washington, and State of Vermont, have invented a new and improved Can-Spout to preserve the contents of the can from evaporation and leakage, and susceptible of being opened and closed at will; and we do declare that the following is a full and exact description of the same.

The nature of our invention consists in the construction of a can-spout susceptible of being opened and closed at will.

To enable others skilled in the art to make and use our invention, we proceed to describe its construction and operation, reference being had to the accompanying drawing, and the letters of reference marked thereon, and making a part of this specification.

Figure 1 represents the can ready for use.

Figure 2 represents the outer tube, which is firmly attached to the upright spout E, the opening A being directly over the top of the spout E.

Figure 3 represents a metallic tube, which we in-

sert within the outer tube, securing it in its place by enlarging the end of the tube, or otherwise.

In this tube there is an opening, B, which, to open the spout, is brought in contact with the opening in the outer tube, allowing the contents of the can to pass out.

To close the spout, the inner tube is turned so as to disconnect the opening.

C represents pin or stop on the inner tube.

D represents the slot in the outer tube, in which the stop C slides.

What we claim as our invention, and desire to secure by Letters Patent, is—

The can herein described, having spout E, tubes, fig. 2 and fig. 3, constructed with openings A and B respectively, and arranged as and for the purpose specified.

T. C. PHINNEY.
C. E. BANCROFT.
